(57) **CLAIM**

The ornamental design for a dispenser, as shown and described.

DESCRIPTION

FIG. 1 is a perspective view of a dispenser showing the new design.

FIG. 2 is a front view of the dispenser of FIG. 1.

FIG. 3 is a first side view of the dispenser of FIG. 1.

FIG. 4 is a second side view of the dispenser of FIG. 1.

FIG. 5 is a back view of the dispenser of FIG. 1; and,

FIG. 6 is a top view of the dispenser of FIG. 1.

Portions of FIGS. 1–6 are shown in dashed lines depict environmental matter only and form no part of the claimed design.
